UNITED STATES PATENT OFFICE.

THOMAS RUSSELL, OF FORT DOUGLAS, UTAH TERRITORY.

COMBINED HANDLE AND BRUSH.

SPECIFICATION forming part of Letters Patent No. 450,041, dated April 7, 1891.

Application filed September 18, 1890. Serial No. 365,327. (No model.)

To all whom it may concern:

Be it known that I, THOMAS RUSSELL, of Fort Douglas, in the county of Salt Lake and Territory of Utah, have invented a new and Improved Combined Handle and Brush, of which the following is a full, clear, and exact description.

My invention relates to improvements in a combined handle and brush, the handle being of the kind adapted to be applied to canes, umbrellas, parasols, and similar articles, and the brush being adapted to be used for brushing clothes, shoes, hats, &c.; and the object of my invention is to produce a handle that may be easily applied to any of the objects mentioned above, and which is constructed in such a manner that the brush may be easily and safely secured therein and as easily removed when desired.

The invention will be hereinafter fully described, and then pointed out in the claim.

Reference is to be had to the accompanying drawings, forming a part of this specification, in which similar letters of reference indicate corresponding parts in all the views.

Figure 1 is a broken side elevation of a cane provided with a handle and brush embodying my invention. Fig. 2 is an enlarged longitudinal section through the upper portion of the cane and handle, showing the manner in which the brush is held within the latter; and Fig. 3 is an enlarged longitudinal section through the cane and handle, showing the brush and a portion of the handle removed.

I have shown the handle and brush embodying my invention applied to a cane; but it may be applied to any light-handled article, if desired.

The handle A is attached to the upper end of a cane B, the cane having a reduced upper end B' to enter the lower end of the handle, and the handle is secured to the cane by means of the screws b, which extend through perforations in the lower portion of the handle and into the reduced end of the cane.

The handle A is hollow and comprises a central body portion A', which is internally screw-threaded at its lower end, as shown at a, and externally at its upper end, as shown at a', a reduced lower portion A², adapted to fit the reduced upper end of the cane B, the up-

per end of said portion being externally screw-threaded to fit the internal screw-thread of the central portion A', and an upper portion A³, which is internally screw-threaded at its lower end to fit the external screw-thread of the central portion A', and which is flared slightly at its upper end and provided with a convex top a², which is shaped to fit easily within the hand.

The brush-body C fits nicely within the central portion A' of the handle A, and is held in place therein by means of the screws c, which extend through the central portion of the handle and into the brush-body. The brush is provided with bristles C' of the usual kind, which extend upward into the top portion A³ of the handle, and the bristle part of the brush should be made in relation to the top of the handle, so that it will fit nicely within the same.

When the brush is to be used, the top A³ is unscrewed from the central portion A' of the handle A, thus exposing the brush, and, if desired, the central portion A' may be unscrewed from the lower portion A² of the handle, so that the central portion A' will form a handle for the brush and the brush may be very conveniently used.

In Fig. 3 I have shown the cane-handle with the brush and the central portion A' of the handle removed and with the top portion A² screwed directly upon the lower portion A² of the handle. A receptacle is thus formed within the handle which affords a safe and convenient place for carrying checks, bank-notes, articles of jewelry, or other small articles of value.

I have shown and described a cane-handle of peculiar form, and the handle shown I find to be a convenient one; but the form is not material, and it may be made in any desired shape so long as it has the sectional parts described and is made hollow to receive the brush.

Having thus described my invention, I claim as new and desire to secure by Letters Patent—

A handle for canes, &c., comprising the lower section or band A², open at both ends and screw-threaded at its upper end, the middle section A', screw-threaded at both ends and provided with a brush projecting from

its upper end, and the top section A³, closed at its upper end, inclosing the brush and screwed at its lower end onto the upper end of the middle section, the lower ends of the bottom section A' being adapted to receive the handle end of a cane, umbrella, or other article, and the lower end of the top section being adapted to screw onto the upper end of

the lower section when the middle section and the brush are removed, substantially as set forth.

THOMAS RUSSELL.
